SUPPORT FOR LADDERS

Albert M. Van Riper, Bayside, Long Island, N. Y.

Application September 4, 1937, Serial No. 162,485

7 Claims. (CL. 228—31)

This invention relates to supports for ladders and has for its general object to provide a support for an ordinary ladder which will permit the ladder to be placed alongside the side of a building upon which work is to be done, and immediately adjacent thereto throughout its length, and to be held safely at the usual ladder inclination to the vertical by means of a single ground-engaging brace member.

When an ordinary ladder is leaned against the side of a building on which work is to be done and is inclined sufficiently to the vertical to form a safe support for the workman, it is obvious that if the ladder be of any substantial length the workman can reach the building from the ladder for only a short distance from its top. There is thus required, for the painting of a house of substantial height, for example, either an extensible ladder or a series of ladders of different lengths and the workman has only a limited field of operation from any one position of any ladder.

An object of the present invention is to provide a simple and conveniently manipulated attachment for an ordinary ladder which will permit the ladder to be placed edgewise to and immediately adjacent to the side of a building on which work is to be done and to be safely supported in this position so that the workman may move freely and confidently up and down the ladder while working within convenient reach of the side wall of the building at all points on the ladder.

An important feature of the invention is the provision of a bracket, preferably attachable to and detachable from the ladder so that it can be used, if desired, with ladders of different lengths, which is constructed to cooperate with a brace member in such manner that when the bracket is braced against the side of a building where the connected ladder is to be located it is substantially equivalent to a bracket support for the ladder positively connected to said side, so far as the character of the support furnished to the ladder is concerned.

Another important feature of the invention is the provision of a hinged link connection between the ladder-supporting bracket and the ladder so that the proper inclination may be given to the bracket and its associated brace member to provide adequate support for the ladder at any desired inclination of the ladder to the vertical.

Still another important feature of the invention is the provision of a pivotal connection be-

tween the brace and the bracket, in combination with a hinged connection between the bracket and the ladder, to permit the convenient raising of the ladder and its bracing in proper supported position by a single operator.

The invention also contemplates the provision of means for varying the length of one of the side-pieces of the ladder to accommodate it to slight inclinations of the ground adjacent to the side of a building.

Other objects and important features of the invention will appear from the following description and claims when considered in connection with the accompanying drawing in which—

Fig. 1 is a perspective view of an embodiment of the present invention, a portion of the ladder and a portion of the brace member being broken away to permit showing the parts on a larger scale;

Fig. 2 is a perspective view illustrating the mode of use of the invention;

Fig. 3 is an elevation also illustrating the mode of use; and

Fig. 4 is a detail view of the ladder side-piece extension attachment for use on sloping ground.

In the illustrative embodiment of the invention the bracket, which when positioned against the side of a building and braced in position provides a support for the ladder connected thereto, may be described as comprising arms or legs 2 and 4 meeting to form a right angle, these legs being connected by side members 6 and 8, which serve two purposes; first, they constitute braces for the legs 2 and 4, and secondly, they serve to confine against lateral movement a brace member 10 which projects substantially into the vertex of the angle between the legs 2 and 4.

The ladder supporting bracket may be formed of any suitable material, such as sheet metal, preferably sheet steel to give the required strength and rigidity. To give the bracket additional stiffness, the sheet metal may be corrugated, as shown, and the outer edges of the side members 6 and 8 may be rolled as shown at 12. Also, for providing better bearing surfaces in the different angular positions which the bracket will assume in use, the legs 2 and 4 may be both corrugated and slightly convex in section.

The leg 2 of the bracket has, as shown, a combined hinge and link connection to a rung 14 of the ladder, the ladder being shown as made up of the usual rungs 14 and side-pieces 16 and 18. This hinge and link connection comprises two

pairs of hinge members 20 hinged to staples 22, positively connected to the leg 2, the hinge members 20 being adapted to embrace the rung 14 and to be held in a lost motion connection thereto by means of a bolt 24 and wing nut 26.

In practice the wing nut is not tightened sufficiently to clamp the hinge members 20 against the rung 14 but allows the hinge members to swing about the rung 14 as an axis and also to slide somewhat over the rung, so that the bolt 24 can move toward and away from the rung. This freely movable link and hinge connection between the leg 2 of the bracket and the ladder rung 14 permits the parts to adjust themselves readily to various relative positions of the bracket, ladder and brace.

The brace member 10, which serves to hold the bracket in ladder supporting position against the side of a building alongside which the ladder is to be located, is preferably pivotally connected to the bracket so that it will not slip out of its position in the slot between the side walls 6 and 8 of the bracket and so that the various parts can readily be manipulated when placing the ladder in position alongside the wall where it is desired to use it. As herein shown, the end of the brace member 10 within the bracket is rounded as illustrated at 28, this rounded end being preferably concentric with the bearing for the bolt 30, provided with the wing nut 32, which serves as the connection between the bracket and the brace member 10 and also as the pivot about which the brace member 10 swings between the two legs 2 and 4.

The manner of use of the invention is shown particularly in Figs. 2 and 3 of the drawing. The ladder, with the connected bracket and brace member, which can be swung into a position in which the brace member 10 is substantially parallel to the ladder side-piece 18, is raised against the side of the building where the ladder is to be located, with the bracket and the brace member upon the outside and with the ladder in a plane substantially parallel to the side of the building, and also with its base preferably substantially where it is desired that the base of the ladder shall rest when the ladder has assumed its inclined position. The ladder is then given a half turn to bring the upright leg 4 of the bracket adjacent to the side of the building and the bottom of the brace 10 is then moved away from the base of the ladder until the ladder has been given the desired inclination, the bottom of the brace 10 being at the same time moved away from the building until the brace member 10 is brought into proper bracing relation to the bracket. The ladder bracket and brace member will then assume the position shown in Figs. 2 and 3.

If the ground adjacent to the building slopes away from the building it may be desirable to provide that side of the ladder which is to rest on the lower level with an extension so that both sides of the ladder will have proper ground support. Suitable extension means for this purpose which permit ready adjustment to different desired extensions are illustrated in detail in Fig. 4 of the drawing. A slidable extension piece 34 having attached thereto near its upper end a short channel member 36 adapted to embrace closely the side-piece 16 of the ladder extends through a clamping device 38 which also comprises a short channel embracing the side-piece 16 of the ladder, the clamping device 38 being provided with an inclined slot 40 in one side of

its channel and having a flange 42 on the other side of its channel on which is mounted a lever arm 44 extending into the slot 40. When the lever arm 44 is moved upward in the slot by the handle 46 it presses the extension piece 34 into tight clamping relation to the side-piece 16 of the ladder. It will be noted that the slot 40 is so located that any tendency of the extension piece 34 to move upwardly will tend to swing the lever arm 44 into tighter clamping relation to the 10 extension piece 34.

What I claim as new is:

1. Ladder supporting means comprising a bracket-like structure having an edge adapted to bear against a wall alongside which the ladder is to be placed and another edge on which the ladder may rest when the first-mentioned edge is in bearing position and having side members defining a slot between said edges for receiving and laterally confining a bracket supporting brace, and means for effecting freely swingable connections between said bracket-like structure and the ladder with which it is to be associated.

2. Ladder supporting means comprising a bracket having intersecting legs, connections by which one leg of said bracket may be so adjustably connected to the ladder that the other leg may bear against a wall alongside which the ladder is to be stationed, said bracket being provided with means for laterally confining a bracket supporting brace extended into the vertex of the angle between said legs.

3. Ladder supporting means comprising a bracket having one leg provided with hinged connecting means by which it may be connected to a ladder rung and another leg adapted to bear against the side of a wall when the ladder to which the first mentioned leg is connected is placed alongside said wall, and means for laterally confining a bracket supporting brace extended into the vertex of the angle between said legs while permitting said brace to swing freely between said legs.

4. Ladder supporting means comprising a bracket having two legs, one of which may be so connected to the ladder that the other will be in position to bear against a wall alongside which the ladder is stationed, a brace for said bracket adapted to swing to different angular relations to the respective legs and means for confining the swinging movement of said brace to movement in the plane determined by said legs.

5. Ladder supporting means comprising a bracket having intersecting legs, link and hinge connections by which one leg of said bracket may be so connected to the rung of a ladder that the bracket may swing bodily into different angular relations to the plane of the ladder and that the said connected bracket leg may also assume different angular relations to the rung, said bracket being provided with side members spaced to form a brace receiving slot between the legs for receiving and guiding a brace extended into the vertex of the angle between said legs.

6. Ladder supporting means comprising a bracket having intersecting legs and spaced side members providing a guide-way for a brace member extended substantially into the vertex of the angle between said legs, means for so connecting one leg of said bracket to a ladder as to permit said ladder to rest on said leg in different angular relations to the plane of the bracket while permitting the other leg of the bracket to be pressed against a wall, alongside which said ladder is to 75

be placed, by means of the aforesaid brace member.

7. Ladder supporting means comprising a bracket-like structure having an edge adapted to bear against a wall alongside which the ladder is to be placed and another edge on which the ladder may rest when the first-mentioned edge is in bearing position and having side members defining a slot between said edges for receiving and laterally confining a bracket supporting

brace, and means for effecting freely swingable connections between said bracket-like structure and the ladder with which it is to be associated, in combination with means for so adjusting the length of one of the ladder side-bars as to accommodate the base of the ladder to the pitch of the ground adjacent to the wall alongside which the ladder is stationed.

ALBERT M. VAN RIPER.
